OFFSHORE DRILLING MEANS

Erle P. Halliburton, Los Angeles, Calif.

Application December 6, 1948, Serial No. 63,831

14 Claims. (Cl. 61—46)

1

This invention relates to offshore drilling apparatus, and particularly to drilling rig supporting means adaptable for positioning over a drilling site which may be beneath a large and deep body of water.

Various structures have heretofore been proposed for use in transporting and supporting well drilling equipment in a manner intended to be suitable for drilling wells below unprotected deep water. Such structures in all cases, however, either constitute permanent developments which may not be moved from the drilling site after drilling operations are completed and which are extremely expensive or constitute structures which, although transportable after drilling, are impractical for the reason that said structures provide no satisfactory means for assuring stability of the structure over the drilling site, either against action of the sea or the wind. In all of the proposed designs, the only restraints provided to resist horizontal movement of the structure during the action of high waves and high winds are vertical members between the primary structure and the water bottom. It is self-evident that as the depth of water in which the proposed structure is to be used increases, the width of the supporting structure must increase in order to provide adequate resistance to upset or collapse the drilling platform. Consequently, truly deep water drilling requires that a tremendously large and heavy structure be built whereby to provide the sufficient base distance, and no provision exists in the prior art whereby this can be achieved in connection with a reasonably compact and light supporting structure.

It is consequently the principal object of this invention to provide a compact, reasonably light but strong structure adapted as a drilling platform and adapted to be stably supported over drilling sites submerged under considerable depths of water.

A further object of the invention is to provide said structure transportable to and from desired drilling sites and adapted to compose its supporting base over varying areas determined by the depth of the water encountered and therefore the distance between the base and top.

Another object of this invention is to provide said supporting base which preferably constitutes telescoping legs as retracted in relationship to the barge or platform itself during transporting, but extendible over any drilling site to form a base for the platform.

Still a further object of the invention is to provide means associated with the supporting struc-

2

ture whereby the barge or drilling platform may be raised from the surface of the sea whereby to be free of the buffeting action of the sea waves.

And yet another object of the invention is to provide portions of the supporting structure for the platform as integrally correlated to assure that the platform is supported evenly and is not tilted or disturbed from a horizontal plane during raising of the platform from the surface of the sea.

Further objects of the invention will appear hereinafter.

In the drawings:

Figure 1 is a side elevational view of a barge or drilling platform embodying the present invention and having its supporting structure or legs in position for moving the barge;

Figure 2 is a top plan view of said barge or platform;

Figure 3 is an end elevational view thereof;

Figure 4 is a view similar to Figure 3 showing the apparatus having its supporting means or legs extending to the bottom;

Figure 5 is another view similar to Figures 3 and 4 but showing the barge or drilling platform raised from the surface of the sea and showing an oil well casing set in the well bore;

Figure 6 is a diagrammatic view showing the hydraulic system for controlling the positions of the barge supporting structure or legs;

Figure 7 is a view similar to Figure 6 showing the valves thereof in a different position;

Figure 8 is a further view similar to Figure 6 showing the valves in yet another position;

Figure 9 is a longitudinal section of one of the legs of the barge supporting apparatus;

Figure 10 is a transverse sectional view of a leg taken on the line 10—10 of Figure 9;

Figure 11 is a longitudinal sectional view taken through one of the hydraulic jacks which control the position of the barge supporting means or legs.

Figure 12 is a longitudinal sectional view of an enlarged lower portion of one of the barge supporting legs.

Figure 13 is a transverse sectional view taken on the line 13—13 of Figure 12; and

Figure 14 is a plan view of a proposed modification of the barge or drilling platform and associated apparatus.

Figure 15 is a side elevational view partly in section and partly diagrammatic, showing a modification of the means for controlling the position of the legs.

55 Referring to the drawings, the general assem-

bly of the structure incorporating this invention consists in a barge 20 which serves as a drilling platform, and is provided with a slot 22 through which drilling operations may take place, the said barge 20 supporting a derrick 24 which may or may not be erected prior to the time the barge reaches the drilling site. The barge is of course of sufficient proportions to contain equipment and supplies for drilling wells and operating connected supporting apparatus, as well as ballast and trim tanks, and may also be equipped with motivating means whereby the barge may be driven to a suitable drilling site.

Attached pivotally to the barge are a plurality of paired telescoping legs 26, shown for clarity as 26 and 26a in some views, which form the principal supporting members once the barge has reached the drilling site. Said legs 26 are extended by hydraulic means hereinafter to be described, whereby the feet 28 connected to the lower extremities of said legs 26 rest upon and may partially submerge in the bottom below the body of water.

After the said feet have contacted the bottom and thus with the legs 26 form a supporting base, the barge or drilling platform 20 is carried upwardly on said legs from the surface of the water out of the way of the waves, as shown in Figure 5. Drilling is commenced, and after completion thereof and after the casing is set and the well finished, the legs 26 are withdrawn or collapsed, settling the barge or platform to the surface of the sea, and the barge then removed from the drilling site, it being noticed that the casing 30 may clear the barge when said barge is moved through the slot 22.

Referring to the device more specifically, the barge 20 constitutes a floating and transportable drilling platform with a longitudinal slot 22 therein and having pairs of telescoping legs 26, each leg pivotally attached to the side of the drilling platform by brackets 32 which form bearings to support the studs 34 extending from bosses 36 welded or otherwise affixed to the uppermost section of the legs 26. Additionally supporting the said legs 26 are trusses 38 which are pivotally attached to straps 38a affixed to the barge and which are also welded or otherwise connected to the upper sections of the said legs 26, it being noted that the pivot line for the trusses 38 is coaxial with the pivot line for the studs 34.

Above the bosses 36 on the upper sections of the legs 26 are studs 42 extending from the leg sections and to which are pivotally affixed the yokes 44 which are connected to piston rods 46 which lead through the hydraulic jacks 48 pivotally supported by the posts 50, said hydraulic jacks 48 being in paired relation and controlling the pivoting of the legs 26 with respect to the barge 20 in manner to be hereinafter described.

The legs 26 comprise a plurality of telescoping sections being adapted to extend as best shown in Figure 9. Each section, said sections forming tubes, is provided with suitable packing means 52 whereby to prevent the passage of fluid from between the sections, and is also provided with suitable stops 54 to prevent over-extension of the legs and stops 56 to prevent over-retraction thereof. The bottommost and smallest section 53 of each leg 26 is provided with a head 60, and below said head is rotatably carried a pin 62 carrying a collar 64 from which extends a bracket 66 carrying rotatably another pin 68 which supports the foot 28, it being noted that each foot

28 is universally supported by each leg 26. It will be appreciated that the structure described shows but one form of a universal connection, and that other means might be used, such as ball and socket joints and the like.

Each foot 28 comprises a hollow, pontoon-like structure of considerable area whereby to distribute the weight of the structure over a sufficient area to prevent penetration of the leg into the bottom, and is provided with transverse plates 70 and longitudinal plates 72 which penetrate into the bottom thereby to prevent any tendency in the feet to slip or skid over the said bottom. The top surface of the said feet 28 are provided with extending threaded studs 74 which are inoperative when the legs 26 are extended but which are adapted to be received in bores in flanges 76 upon brackets 78 extending from the barge itself when the legs 26 are retracted. Bolts 80 may be screwed over the studs 74 when said legs are so retracted and thus is provided additional supporting means for the feet and legs during transport of the barge to and from the drilling site, it being noted that in hollow condition the feet 28 themselves serve as pontoon supports at the surface of the water.

In the preferred embodiment of the invention, the extension of the legs 26 and feet 28 after removal of the bolts 80, the positioning of said members, and the raising of the barge from the surface of the water is all accomplished by hydraulic means.

The top of the uppermost section of each leg 26 is provided with a head 82 and affixed thereto is a bearing 84 which rotatably carries the uppermost section of a telescoping tube 86, said tube extending through the head 82 and being connected with a conduit 88. The tube 86 is provided with packing means 90 and is adapted to telescopically extend in conjunction with the leg 26, a keyway 92 being provided in said tube coacting with suitable keying means to prevent relative rotation between the various sections of the tube. The lowermost section of the tube 86 opens into a three-way selector valve 94 whose operation will be hereinafter described, and to the upper portion of said tube is welded a handle 96 by which the tube may be turned as a unit to control the said valve 94. The conduit 88 is selectively connected to a water pump or to an air pump, not shown but which may be accommodated on the deck of the barge.

The valve 94 comprises a valve body 98, integral with the lowermost section of the tube 86, and set within a valve housing 100 and turnable therein. Said valve body is provided with a slot 102, a passage 104 and a passage 106, adapted to coordinate for operational purposes with a conduit 108 leading through the valve housing, with a conduit 110, a conduit 112 and a conduit 114. For the purpose of lowering the legs 26 and feet 28, the valve body 98 is turned to such position that the passage 106 connects with conduit 114 whereby pumping of water 65 through the conduit 88, tube 86, valve body 98, passage 106 and conduit 114 passes said fluid through a float valve 116 supported within the foot 28 into the interior of said foot 28. The foot 28 and various sections of the legs 26 will sink at a speed the function of the amount of water in each foot 28. Thus, the more water in each foot, the faster the foot and leg will sink; but if it is desired to slow the rate of sinking, air may be pumped through the conduit 88 and thereafter through the means just set forth to

the foot 28. By means of a gooseneck 118 leading to ports 120 in the foot 28, water is thus expelled from said foot, the foot is rendered relatively more buoyant, and the speed of descent is checked.

Again the rate of speed of descent may be increased considerably where desired by filling the legs 26 themselves with fluid. A conduit 122 controlled by a valve 124 leads from a fluid pump to each leg 26 through a port in the head 82 for this purpose. When it is desired to fill a leg 26 with fluid, the tube 86 is rotated to turn the valve body 98 to a position whereby the passage 104 registers with the conduit 110, the said conduit 110 leading to a cylinder 126 whereby to force a piston carrying a valve 128 outwardly, causing said valve to seat in a port in the chamber 130, said chamber 130 normally providing egress for fluid within the leg 26. After thus closing the leg 26, fluid is forced into said leg through the conduit 122 and under pressure aids in extending same, it being noted that a relief valve 131 is provided in the head 82 of each leg 26 whereby to bleed air from said leg.

After the foot 28 has reached the bottom, the legs 26 will not have been extended fully, the remaining potential extension being available to lift the barge or platform 20 from the surface of the water. This is done by applying more pressure to the fluid from the conduit 122 into the leg 26 and as fluid is forced thereinto the legs 26 will extend further, raising the barge 20. Such raising of the barge is accomplished under the control of the pairs of differential jacks 48 in manner to be hereinafter described.

After the barge has been lifted from the surface of the water and drilling has been completed and it is desired to move to a new site, the foregoing hydraulic system is adapted to assist in the raising of the legs and feet. The conduits 122 are opened to drain, thus relieving the fluid pressure within the legs 26 and permitting the barge to settle back to the surface of the water. Thereafter, the tube 86, and thus the valve body 98, is turned to register the passage 104 with the conduit 112 so that fluid pressure will force the valve 128 to open position with respect to the chamber 130, thus permitting free draining of the leg 26. It will be noted that by virtue of the slot 102 in the valve body 98, the inoperative side of the cylinder 126 is permitted to drain through a spring-loaded ball valve 132. After opening the leg 26, the valve body 98 is again rotated, this time again to register the passage 106 with the conduit 114, whereupon air is forced into the tube 86 and into the foot 28, forcing the water therein out through the conduit 118 and ports 120. The buoyancy of the said foot will cause the sections of the leg 26 to telescope and retract to the surface, a draining of the fluid in said leg occurring through the chamber 130. It will be noted that the provision of the ports 120 at the bottom of the feet 28 not only provide a suction-breaking means at the bottom of said feet but also during the jetting of the water in each foot, provide a means for washing away adhesive mud, sand, and the like. When the legs 26 are fully telescoped and the feet 28 have risen to the surface, the bolts 80 are threaded over the threaded studs 74, thereby fully supporting the feet and legs for transport of the barge.

The foregoing has described the means associated with the legs and feet for extending and retracting same. In order to control the angular disposition of the legs with respect to the

barge or platform 20, there is provided, as shown partially schematically in Figures 6, 7 and 8, pairs of jacks 48, each pair referred to for convenience as 48 and 48a, adapted each individually to control its respective leg and each pair adapted, if desired, to coordinate the pivotal movement of facing pairs of said legs 26. As heretofore stated, each jack 48 is itself pivotally supported on a post 50 and connected through a piston rod 46 and yoke 44 to the uppermost section of each leg 26. Slidable in each jack 48 is a piston 134 connected to the piston rod 46. On either side of said piston 134 and leading from the jack 48 is a divided conduit, the conduit on the exterior side of said piston 134 in a jack 48 leading through one of a pair of two-position valve elements 135 and 136a commonly actuated in a single valve 138 to an open and closed position to the interior side of its matching jack 48a, through a conduit 140. Conversely, the divided conduit leading from the exterior side of the piston 134a in jack 48a passes by conduit 140a through the valve element 136a to the interior side of the jack 48. The exterior side of the jack 48 also leads through a conduit 142 to a four-position selector valve 144 having three commonly actuated valve elements 146, 148 and 150, said valve 144 leading in turn to a fluid pump and to a reservoir. Similarly, the conduit 142a leading from the jack 48a leads to a comparable valve 144a having valve elements 146a, 148a, 150a and said valve 144a leads to a fluid pump and reservoir. Conduits 152 and 152a lead, respectively, from the interior sides of jacks 48 and 48a to the valves 144 and 144a.

Referring to Figures 6, 7 and 8 and particularly to Figure 6 and the jack 48, it will be seen that the disposition of the valve elements 146, 148 and 150 causes fluid to lead from the pump 40 to the interior side of the jack 48 and with the valve 138 closed, the leg 26 is pivoted to move the foot 28 inwardly with respect to the barge 20 and independently of any other leg including its matching leg 26a. Again referring particularly to Figure 7 and the jack 48a, it will be seen that disposition of the valve elements 146a, 148a and 150a pass fluid to the exterior of the jack 48a, and with the valve 138 closed pivots the leg 26a so that the foot 28a moves outwardly from the barge 20.

It is to be noted that in both Figures 6 and 7 the legs 26 and 26a are actuated independently, since the valve 138 is closed and since no communication exists between jacks through the conduits 140 and 140a. In Figure 6 it will be noted that due to the disposition of the elements of the valve 144a the leg 26a is locked against pivoting. In Figure 7, since communication is provided between the exterior and interior sides of the jack 48 through the valve element 148, free and unrestricted pivoting in either direction of the leg 26 is permitted.

Thus it will be seen by Figures 6 and 7 that with the valve 138 closed, the valve 144 and its duplicate, the valve 144a, permit in the various dispositions of their elements an independent controlling of the various legs whereby to pivot said legs to move a foot 28 inwardly with respect to the barge or outwardly with respect to the barge, permit a locking of the leg, or permit a free and unrestricted pivoting thereof.

Figure 8 shows the valve 138 in open position, thus providing communication between the exterior and interior sides of matching jacks 48 and 48a through the conduits 140 and 140a. It

is contemplated that such communication will be permitted only when the valves 144 and 144a and their elements are in a position which, but for the open position of valve 138, would lock their respective jacks, i. e., the position shown of valve 144a in Figure 6. Since the valve 138 is open and communication permitted between the conduits 148 and 140a, it will be seen that pivoting in either direction is permitted in the legs 26 or in the legs 26a, with the proviso that if the leg 26 be pivoted, a corresponding pivoting must take place in the leg 26a and such pivoting must be in the same direction.

It will be noted that there has not been shown in the drawings the various pumps, valves, and the like heretofore described in connection with the apparatus. Said pumps, valves, and associated mechanism may be placed upon the barge or platform 20 in any suitable space and enclosed in, for example, the engine room or a separate control room. In addition to the trusses 38 and the like for supporting the legs 26, there have been provided various guy wires or cables and the like for the purpose of aiding in stabilizing the supporting structure. Thus there have been provided cables 154 and 156 connected to the feet 28 and to winches (not shown) on the barge 20 itself which may be used to in part control the angular disposition of the feet 28 upon extension of the legs 26. Moreover, cables 158 may be provided connecting various pairs of feet 28 to prevent undesired spreading of the supporting structure and to minimize the danger of collapse thereof. Again, to prevent undesired spreading of the feet in a longitudinal direction, cables 160 are shown connecting the feet longitudinally. And finally, it will be appreciated that during drilling operations, any suitable bracing member 162, as a bolted-down beam, may be provided across the slot 22 to add rigidity to the barge or platform.

In the general operation of the drilling platform or barge, the said barge is transported to the drilling site and the feet 28 unbolted. Thereafter, to attain the position shown in Figure 4, the desired angular disposition of the legs is achieved by manipulation of the valves 144 and 144a and application of fluid pressure to the jacks 48 and 48a, the valve 138 remaining closed during this operation. The legs 26 may then be locked in their proper angular dispositions, as shown schematically in Figure 6, with respect to the jack 48a. For each leg, the handle 96 is then actuated to turn the valve body 98 and fluid is pumped through the conduit 88 and on into the feet 28 whereby said feet and the legs 26 sink to the bottom. Thereafter the valve 138 is opened and the valves 144 and 144a being in normally locked position, each leg 26 is free to pivot with respect to the barge 20, but its matching leg must correspondingly pivot whereby the barge may be maintained during any pivoting in a horizontal plane. Upon assuring that the chamber 130 is closed to prevent leakage of fluid from the legs 26, fluid is pumped into the said legs 26 and they are further extended to lift the barge 20 from the surface of the water, it being noted that in this operation the legs 26 will pivot outwardly but each pair in unison as the barge leaves the surface of the water. The valve 138 is then closed which provides a locking of the various jacks 48 and 48a and consequently the legs 26, and the barge and supporting structure is ready for any drilling operations desired.

After drilling is completed and it is desired to move the barge, the valve 138 is first opened and

fluid allowed to exit from the conduits 122 whereupon the legs will partially telescope and the barge settle to the surface of the water. For each leg, by the handle 96, the valve body 98 is turned to open the chamber 130 and thus vent each of the legs 26, and then turned again to connect each tube 86 with its foot 28. Air is pumped into the feet 28 and their natural buoyancy causes a telescoping of the legs 26 and a withdrawal to the barge. The valves 144 and 144a are adjusted to enable fluid pressure through the jacks 48 and 48a to pivot the legs 26 to their upright positions and the feet 28 thereupon bolted to the brackets 78, whereupon the barge can depart from the completed well.

It is obvious that various departures from the mode of operation above described are available. For example, in preparation for drilling, the legs on one side of the barge may be extended in a substantially vertical position until their feet 28 reach the bottom, whereupon the jacks on the proper side may be used to dispose said extended legs in the desired angular position, after which the legs on the other side may be disposed in their desired angular positions and thereafter lowered until their feet 28 rest upon the bottom. Again, as heretofore noted, judicious handling of the valve means 94 and associated pumps may be used to control the rate of descent or even the rate of ascent of the feet 28 and the legs 26, and descent of the legs 26 may be speeded up by introducing fluid into said legs 26 at the same time fluid is introduced into the feet 28.

Figure 14 shows a modification in the structure whereby, instead of a long and narrow barge, the barge itself is substantially square. In the modification shown, the legs and associated mechanism are mounted one on each side of the barge and the facing legs are integrated in control just as are the matching legs in the preferred embodiment. The operation of this modification, so far as concerns the respective pairs of legs, is precisely the same as the operation of the more narrowly shaped barge, and like parts in the principal embodiment correspond to like parts on the modification. The principal advantage of the modification shown is that where the well drilling is to be of such a nature as not to require heavier machinery, materials and the like, as in shallow well drilling, said embodiment provides a lighter, more compact and less expensive structure.

Figure 15 shows a modification in the structure whereby, in order to control the angular disposition of the legs 26, a mechanical system is used instead of the previously described hydraulic jack system. Between each pair of legs 26 is provided a differential gearing mechanism which comprises a conventional gear box 160 containing sun gears 162 and 164 and planetary gears 166 and 168, said planetary gears 166 and 168 being adapted to rotate freely on the shafts 170 and 172. Carried by the structure is the ring gear 174 which engages a pinion 176 affixed to a shaft 178 which has associated with it a brake drum 180. The shaft 178 is driven by suitable power means such as a motor, which is not shown.

The sun gear 162 is keyed to a shaft 182 which extends out of the gear box through a brake drum 184 into a clutching mechanism 186. The clutching mechanism 186 is controlled by a lever 188 and operates a shaft 190 to which is affixed a bevel gear 192. Said bevel gear 192 engages another bevel gear 194 on a shaft 196 supported in the bearing structures 198 which are shown partially diagrammatically. A reel 200 is carried

on the shaft 196 and in turn carries a cable 202 passing around a sheave 204 and connected on opposite sides to the upper portion of the leg 26. The sheave 204 is supported by truss means 205 rigidly affixed to the brackets 32.

Similarly, the sun gear 164 is keyed to shaft 208 passing through brake drum 210 to clutch 212 controlled by the lever 214. On the other side of said clutch is a shaft 216 carrying bevel gear 218 which engages a bevel gear 220 carried by the shaft 222. It will be noted that the bevel gear 220 is in opposite relationship to the bevel gear 218 from that relationship between the bevel gears 192 and 194.

The shaft 222, supported in the diagrammatically shown bearings 224, carries a reel 226 which in turn carries a cable 228. The cable 228 passes around a sheave 230 which is carried by the truss 232 and is connected to the leg 26a.

As with the prior described hydraulic jack system, the above mechanical system provides a differential means for controlling the angular disposition of the legs 26 and 26a in respect to the barge. If it be desired to move the leg 26 independently of the leg 26a, the operator will lock the shaft 208 by means of the brake drum 210, thus rendering the leg 26a immovable and may then apply power in the direction desired to the shaft 178. By virtue of the ring gear 174, the gear box 160 will rotate, rotating in turn the sun gear 162 and the shaft 182. With the clutch 186 engaged, this will drive the reel 200 and thus the cable 202 to dispose the leg 26 in its desired position. Of course, it is appreciated that it is unnecessary during this operation to render the leg 26a immovable inasmuch as the clutch 212 can be disengaged.

It will thus be seen by the foregoing description that through the differential system described, either the leg 26 or the leg 26a may be angularly disposed independent of its matching leg. As heretofore described, however, it is desirable that means be afforded whereby angular movement of one leg be accompanied by an equivalent angular movement in the other leg as when the barge is ready to be lifted from the surface of the body of water over which drilling is to take place. This is accomplished by freeing the two brake drums 184 and 210 by engaging the two clutches 186 and 212, and by simply locking the shaft 178 by means of the brake drum 180. In this condition, when fluid is pumped into the legs 26 and 26a, in order to raise the barge with respect to the surface of the body of water, angular movement in either one of the legs is accompanied by equal angular movement in the other. Thus, when the leg 26 pivots counterclockwise, the reel 200 will cause the shaft 196 to turn, and through the bevel gears 194 and 192, the shaft 182 will likewise turn. Through the sun gear 162, the planetary gears 166 and 168 and the sun gear 164, the shaft 208 will turn in an opposite direction from the shaft 182, and through the bevel gears 218 and 220, cause the reel 226 to rotate. Rotation of the reel 226 drives the cable 228 to cause a clockwise pivoting of the leg 26a corresponding with the counterclockwise pivoting of the leg 26. It is, of course, apparent that locking legs 26 and 26a in desired angular disposition may be accomplished by locking the shafts 182 and 208 by the brake drums 184 and 210, provided that the clutches 186 and 212 are engaged.

While there has been described what is at present considered a preferred embodiment of the present invention, it will be apparent to

those skilled in the art that various modifications and changes may be made without departing from the essence of the invention, and it is intended to cover herein all such modifications and changes as come within the true scope and spirit of the appended claims.

I claim:

1. A barge for supporting well drilling structure over a body of water comprising: a barge body; telescoping supporting legs pivotally connected thereto, said legs, when extended being of sufficient length to lift said barge body above the surface of said water and to provide a base in excess of the width of said barge body; and an hydraulic system operable to pump fluid into said legs to extend said legs; and air pumps connected to said system whereby to evacuate said fluid from said legs to permit floating retraction thereof.
2. A barge for supporting well drilling structure over a body of water comprising: a barge body; pairs of facing extendable legs pivotally connected thereto, said legs, when extended, being of sufficient length to lift said barge body above the surface of said water and to provide a base in excess of the width of said barge body; and an hydraulic system operable to pump fluid into said legs to extend said legs.
3. A barge for supporting well drilling structure over a body of water comprising: a barge body; extendable supporting legs pivotally connected thereto, said legs, when extended, being of sufficient length to lift said barge body above the surface of said water and to provide a base in excess of the width of said barge body; and hydraulic jacks cooperatively associated with said legs to control the angular disposition of said legs in relation to said barge body.
4. A barge for supporting well drilling structure over a body of water comprising: a barge body; extendable supporting legs pivotally connected thereto, said legs, when extended, being of sufficient length to lift said barge body above the surface of said water and to provide a base in excess of the width of said barge body; and differential gear linkage cooperatively associated with said legs to control the angular disposition of said legs in relation to said barge body.
5. A barge for supporting well drilling structure over a body of water comprising: a barge body; pairs of facing extendable legs pivotally connected thereto, the legs of each pair having each a predetermined angular disposition with respect to said barge body, and being restrained each to vary its angular disposition in response to any variance in the angular disposition of the other; and an hydraulic system operable to pump fluid into said legs to extend said legs to provide supporting structure for said barge body of predetermined base width.
6. A barge for supporting well drilling structure over a body of water comprising: a barge body; pairs of facing extendable legs pivotally connected thereto, the legs of each pair having each a predetermined angular disposition with respect to said barge body, and being differentially restrained each to vary its angular disposition in response to any variance in the angular disposition of the other; and an hydraulic system operable to pump fluid into said legs to extend said legs to provide supporting structure for said barge body of predetermined base width.
7. A barge for supporting well drilling structure over a body of water comprising: a barge body; pairs of facing telescoping legs pivotally

connected thereto, the legs of each pair having each a predetermined angular disposition with respect to said barge body, and being restrained each to vary its angular disposition in response to any variance in the angular disposition of the other, said leg pairs being extendable to sufficient length to provide a base of predetermined width for said barge body and to lift said barge body from said water; and an hydraulic system operable to pump fluid into said legs to extend said legs.

8. A barge for supporting well drilling structure over a body of water comprising: a barge body; pairs of facing telescoping legs pivotally connected thereto, the legs of each pair having each a predetermined angular disposition with respect to said barge body, and being differentially restrained each to vary its angular disposition in response to any variance in the angular disposition of the other, said leg pairs being extendable to sufficient length to provide a base of predetermined width for said barge body and to lift said barge body from said water; and an hydraulic system operable to pump fluid into said legs to extend said legs.

9. A barge for supporting well drilling structure over a body of water comprising: a barge body; pairs of facing telescoping legs pivotally connected thereto, the legs of each pair having each a predetermined angular disposition with respect to said barge body, means adapted to restrain each leg to vary its angular disposition in response to any variance in the angular disposition of the other, said leg pairs being extendable to sufficient length to provide a base of predetermined width for said barge body and to lift said barge body from said water, said means including differential hydraulic jacks; and an hydraulic system operable to pump fluid into said legs to extend said legs.

10. A barge for supporting well drilling structure over a body of water comprising: a barge body; pairs of facing telescoping legs pivotally connected thereto, the legs of each pair having each a predetermined angular disposition with respect to said barge body, means adapted to restrain each leg to vary its angular disposition in response to any variance in the angular disposition of the other, said leg pairs being extendable to sufficient length to provide a base of predetermined width for said barge body and to lift said barge body from said water, said means including a differential gear linkage; and an hydraulic system operable to pump fluid into said legs to extend said legs.

11. A barge for supporting well drilling structure over a body of water comprising: a barge body; pairs of facing extendible legs pivotally connected thereto, the legs of each pair having each a predetermined angular disposition with respect to said barge body, and being restrained each to vary said angular disposition in response

to any variance in the angular disposition of the other; and means for extending said legs to lift said barge body above said water and to provide a base for said barge body.

5 12. A barge for supporting well drilling structure over a body of water comprising: a barge body; pairs of facing extendible legs pivotally connected thereto, the legs of each pair having each a predetermined angular disposition with respect to said barge body, and being differentially restrained each to vary said angular disposition in response to any variance in the angular disposition of the other; and means for extending said legs to lift said barge body above said water and to provide a base for said barge body.

13. A barge for supporting well drilling structure over a body of water comprising: a barge body; pairs of facing extendible legs pivotally connected thereto, the legs of each pair having each a predetermined angular disposition with respect to said barge body; hydraulic jacks cooperatively associated with the legs of each pair to restrain each leg to vary its angular disposition in response to any variance in the angular disposition of the other; and means for extending said legs to lift said barge body above said water and to provide a base for said barge body.

14. A barge for supporting well drilling structure over a body of water comprising: a barge body; pairs of facing extendible legs pivotally connected thereto, the legs of each pair having each a predetermined angular disposition with respect to said barge body; differential gear linkage cooperatively associated with the legs of each pair to restrain each leg to vary its angular disposition in response to any variance in the angular disposition of the other; and means for extending said legs to lift said barge body above said water and to provide a base for said barge body.

ERLE P. HALLIBURTON.
